5 Claims. (Cl. 323—89)

This invention relates to magnetic current-control devices. More particularly, this invention relates to signal amplifying apparatus of the type which includes output windings wound on saturable magnetic core material and used to vary the flow of current from an A.C. energizing source in accordance with signals fed to a control winding on the core.

In such magnetic amplifying equipment provided heretofore, there has been a problem in achieving desired high-gain characteristics without introducing instability, e.g. continuous oscillation, hunting, etc. It has been found that these difficulties apparently have been due at least in part to the generation of harmonic voltages in the output windings. Although these windings are energized by a single-frequency source of current, the saturation characteristics of the magnetic material produce sharp discontinuities in the current flow resulting in the development of a wide range of harmonic components.

Such harmonic components are, of course, coupled from the output windings to the amplifier control winding which also is wound on the magnetic core. From the control winding, the harmonic components feed back to the output circuit of the equipment which drives the magnetic amplifier, for example a preceding stage of amplification, and disturb the functioning of the system. The problem is particularly acute when the system is arranged to have high amplification gain, since any disturbance will be greatly magnified and will tend to produce oscillations and other series effects detrimental to proper functioning of the apparatus.

The problem can be alleviated to some extent by inserting a loss element such as a resistor in series with the magnetic amplifier control winding. The resistor tends to absorb the harmonic components so that they cannot disturb the functioning of the system. However, a resistor large enough to eliminate undesired interaction effects will normally also decrease the system amplification gain a substantial amount.

In accordance with one aspect of the present invention, these difficulties are effectively eliminated by providing the magnetic amplifier with an additional winding which is short-circuited to permit virtually unimpeded flow of current around the winding turns. It has been found that such a short-circuited winding apparently absorbs the generated harmonic components without however substantially affecting the flow of signal current into the magnetic amplifier control winding. As a result, interaction disturbances are minimized, and the system can be arranged to have high gain without the oscillation and hunting difficulties previously encountered.

The short-circuited winding arrangement is particularly suited for magnetic amplifiers of the balanced, full-wave type. In this type of amplifier, as described hereinbelow in detail, there are two A.C. energized output windings, each wound on a separate magnetic core, and each energized on alternate half-cycles of the A.C. supply. It has been found that a short-circuited winding wound around both of the cores not only minimizes the disturbing effects

2

of interaction discussed above, but also improves the performance of the amplifier, e.g. increased gain. In this regard, it is believed that the close coupling between the cores provided by the short-circuited winding produces a "resetting action" which conditions the magnetic material of each core during the half-cycle that its output winding is not energized. This resetting action apparently augments the flux produced by the magnetic amplifier control winding, and thereby improves the efficiency of control exercised over the flow of current through the A.C. energized output windings.

Accordingly, it is an object of the present invention to provide magnetic amplifying apparatus that is superior to such apparatus provided heretofore. It is a further object of this invention to provide such apparatus having improved stability characteristics. It is a still further object to provide a magnetic amplifier that is economical to construct yet capable of high-gain performance. Other objects, aspects and advantages of this invention will be pointed out in, or apparent from, the following description of preferred embodiments considered together with the accompanying drawings, in which:

Figure 1 is a schematic diagram of a two-stage magnetic amplifier constructed in accordance with the present invention;

Figures 2A and 2B are pictorial representations of the voltage waveforms in the output windings of the amplifier of Figure 1; and

Figure 3 is a schematic diagram of a modified form of magnetic amplifier.

Referring now to Figure 1, there is diagrammatically shown a magnetic amplifier having two stages generally indicated at 10 and 12. The first stage of amplification comprises a pair of separate identical toroidal cores 14 and 16 of saturable magnetic material surrounded by a number of windings as will be described. Although these windings are shown in different positions around the cores, it will be understood that in practice the windings are all evenly distributed about the cores in a multi-layer arrangement.

Wound about each of the cores 14 and 16 respectively is a corresponding pair of output "gate" windings 18 and 20 connected together at a common point 22. These windings are energized through rectifiers 24 and 26 which are connected to the opposite ends of one secondary winding 28 of a power transformer generally indicated at 30. The primary winding 32 of this transformer is connected to a source of A.C. energizing potential, e.g. the usual 120 volts, 60 cycle power line. The secondary winding 28 includes a center-tap connection 34 which is connected through a control winding 36 of the second stage of amplification 12 back to the common point 22 between the gate windings 18 and 20.

Accordingly, the output circuit for the first stage 10 is a balanced full-wave arrangement wherein the gate windings 18 and 20 are energized on alternate half-cycles of the A.C. energizing source. During the firing half-cycle for either gate winding, the voltage across the winding builds up sinusoidally (references 38 and 40 of Figures 2A and 2B) until the magnetic material of the corresponding core saturates. At this point (references 42 and 44, Figures 2A and 2B) the voltage across the winding drops essentially to zero, and current flows through the control winding 36 of the second stage 12 for the remainder of the half-cycle. The rectifiers 24 and 26 are polarized so that the current flowing through the control winding 36 will always be in the same direction, and the average magnitude of this current varies in accordance with changes in the point at which saturation occurs.

The point in the energizing cycle at which saturation of cores 14 and 16 occurs is determined primarily by the level of input current flowing through a control winding

46 which encircles both of these cores. In addition, the saturation point is set for a given input current level by a conventional bias winding 48 wound around both the cores and supplied with D.C. current from a rectifier power supply generally indicated at 50.

To avoid the disturbing effects of harmonics generated in the gate windings 18 and 20, the cores 14 and 16 also are provided with a short-circuited winding 52 which is wound around both of the cores. This winding, because it is inductively coupled to the magnetic flux paths of the amplifier cores, absorbs the harmonic components generated in the gate windings due to the sharp discontinuities of current flow through these windings. Furthermore, the current flowing in the short-circuited winding while either one of the gate windings is energized produces flux in the core associated with the other gate winding, and this flux aids the control winding 46 in conditioning that core for proper operation during the next succeeding half-cycle of the A.C. energizing source.

The second stage of amplification 12 comprises a pair of identical toroidal cores 54 and 56 of saturable magnetic material arranged in a manner similar to cores 14 and 16 previously described, and biased to the proper magnetic operating conditions by the interstage circulating current passing through the control winding 36. The cores 54 and 56 carry respective gate windings 58 and 60 which are connected with rectifiers 62 and 64 as a balanced full-wave output circuit energized by another secondary winding 66 on the transformer 30. The center tap 68 of this secondary winding is connected through a load resistor 70 and a negative feedback circuit 72 to the common point 74 between the gate windings 58 and 60. The output signal of the amplifier is smoothed by a filter capacitor 76 connected between the common point 74 and the center tap 68.

The feedback circuit 72 leads the amplifier output current through a pair of feedback windings 78 and 80 each wound on a respective one of the magnetic cores 14 and 16 of the first amplifier stage 10, and thereby effectively "nulls" the control winding input signal. The feedback circuit also couples changes in the output signal through a capacitor 82 and a resistor 84 to a negative feedback winding 86 which is wound around both of the magnetic cores 54 and 56 of the second stage 12, and which serves to stabilize the amplifier output.

As in the previous stage 10 of amplification, the cores 54 and 56 also are provided with a short-circuited winding 88 which encircles both of these cores and serves to provide a low impedance path for the flow of harmonic signals. A particular advantage is that this winding effectively decouples the second stage 12 from the output circuit of the first stage 10, and thereby assures more stable operation of the overall amplifier.

Winding specifications for an amplifier constructed as described above and found to operate satisfactorily are as follows:

(1) Cores 14 and 16—Core material of the square-hysteresis type comprising 3 mil tape, e.g. "HYMU 80" as manufactured by Magnetics Incorporated under No. 50,003-3D;

(2) Gate windings 18 and 20—1320 turns of AWG No. 34 copper wire with an electrical resistance of 33 ohms each.

(3) Control winding 46—1000 turns of AWG No. 38 copper wire with an electrical resistance of 150 ohms.

(4) Bias winding 48—500 turns of AWG No. 38 copper wire with an electrical resistance of 104.5 ohms.

(5) Short-circuited winding 52—500 turns of AWG No. 40 copper wire with an electrical resistance of 108 ohms.

(6) Feedback windings 78 and 80—90 turns of AWG No. 34 copper wire with an electrical resistance of 2.5 ohms each.

(7) Cores 54 and 56—Core material of the square-hysteresis type comprising 4 mil tape, e.g. "Orthonol" 75

as manufactured by Magnetics Incorporated under No. 50,026-4A;

(8) Gate windings 58 and 60—2850 turns of AWG No. 32 copper wire with an electrical resistance of 77 ohms.

(9) Control winding 36—200 turns of AWG No. 36 copper wire with an electrical resistance of 26 ohms.

(10) Short-circuited winding 88—7 turns of AWG No. 22 copper wire with an electrical resistance of approximately 0.03 ohm.

(11) Feedback winding 86—1000 turns of AWG No. 38 copper wire with an electrical resistance of 200 ohms.

Figure 3 shows a modified amplifier adapted to accept A.C. input signals and to produce bi-polar output signals in accordance with the phase of the input signal. This amplifier includes two separate amplifier sections generally indicated at 90 and 92 having their respective input circuits connected in series and their respective output circuits connected differentially.

Each of these amplifier sections includes a pair of toroidal cores 94, 96 and 98, 100 with each pair of cores arranged in coaxial side-by-side configuration. These cores are provided with respective gate windings 102, 104 and 106, 108, the corresponding pairs of which are connected in balanced full-wave output circuits as described with reference to Figure 1. The gate windings are energized by a power transformer 110 through rectifiers 112, 114 and 116, 118, and the respective output circuits include load resistors 120 and 122 which are connected together at a common point 124.

The magnetic cores also are provided with control windings 126, 128 and 130, 132 connected to input terminals 134 and 136. The first pair of control windings 126, 128 are connected together in parallel, as are the second pair of control windings 130, 132. However, the winding pairs are connected in series relationship with respect to the input terminals 134 and 136 so that the input current flowing through the sections 90 and 92 will always be equal.

Bias windings 138 and 140 are wound around the cores and are supplied with D.C. current by a rectifier power supply 142. A balancing potentiometer 144 is connected across the power supply output to permit a fine adjustment of zero balance between the two amplifier sections 90 and 92.

The amplifier includes a pair of output terminals 146 and 148 connected to remote ends of the load resistors 120 and 122 respectively so that any difference in potential drop across the resistors will appear as an output voltage at these terminals. With zero input current through the control windings 126, 128 and 130, 132, the amplifier is adjusted so that equal currents will flow through these load resistors, and accordingly the output voltage will be zero. With an A.C. input signal of a given phase, one of the load resistors will carry more current than the other, and an output voltage of corresponding polarity will be produced. If the input signal phase is reversed, the other load resistor will carry the greater current, and the output voltage polarity will accordingly reverse.

With the control windings 126 and 128 connected in parallel as described above, these two windings together act as a short-circuited winding insofar as the two magnetic cores 94 and 96 of the first amplifier section 90 are concerned. Similarly, the control windings 130 and 132 act as a short-circuited winding for the second section 92. Accordingly, these control windings serve the dual function of controlling the output signal of the magnetic amplifier and also absorbing harmonic components generated in the gate windings 102, 104, 106 and 108.

Each section 90 and 92 of the amplifier also is provided with a corresponding negative feedback winding 150 and 152 both of which are connected in series with a current-limiting resistor 154 across the output terminals 146 and 148. Whenever an output voltage appears across these terminals, the resulting flow of feedback current aids in stabilizing the amplifier operation.

It should also be noted that the Figure 3 arrangement can be used as a D.-C. amplifier by making appropriate changes to the polarity of the control windings.

Although specific preferred embodiments of the invention have been set forth in detail, it is desired to emphasize that these are not intended to be exhaustive or necessarily limitative; on the contrary, the showing herein is for the purpose of illustrating the invention and thus to enable others skilled in the art to adapt the invention in such ways as meet the requirements of particular applications, it being understood that various modifications may be made without departing from the scope of the invention as limited by the prior art.

I claim:

1. Magnetic amplifying apparatus comprising, in combination, saturable magnetic material establishing first and second pairs of closed flux paths, first and second pairs of control windings each wound about a corresponding one of said flux paths, first circuit means connecting said first pair of control windings together in parallel to form a short-circuited winding encircling said first pair of flux paths, second circuit means connecting said second pair of control windings together in parallel to form a short-circuited winding encircling said second pair of flux paths, input circuit means connecting said first and second pairs of control windings together in series relationship, first and second output winding means inductively coupled to said first and second pairs of flux paths respectively, energizing circuit means including rectifier means for feeding rectified A.C. current to said output winding means, first and second load elements connected to said first and second output winding means respectively, and an output circuit coupling said first and second load elements together differentially whereby any unbalance in the average current carried by said elements produces a corresponding output voltage.

2. A magnetic amplifier comprising, in combination, a pair of coaxially-positioned balanced toroidal magnetic cores each establishing a closed flux path, a pair of output windings each wound around a respective one of said toroidal cores, an alternating-current energizing circuit arranged to feed current through said output windings respectively on alternate half-cycles of the A.C. supply voltage, a load element connected in series with said energizing circuit to carry said current, control winding means surrounding both of said cores, and circuit means establishing a short-circuited electrically-conductive path surrounding both of said cores, said electrically-conductive path being so disposed with respect to said cores that a current flowing around said path will produce in said cores respective fluxes having the same directional relationship with respect to the corresponding fluxes produced in said cores by said output windings during the firing half-cycles thereof.

3. Magnetic amplifying apparatus for amplifying A.C. signals and comprising saturable magnetic material defining first and second closed flux paths, first and second output windings inductively coupled to said flux paths respectively, a full-wave A.C. energizing circuit including rectifier means for feeding half-wave A.C. current to said output windings on opposite half cycles of the A.C. supply, first and second control windings for said flux paths

respectively, an input circuit for feeding an A.C. control signal to both of said control windings, and circuit means conductively connecting said two control windings directly in parallel with each other and with said input circuit, to form a short-circuited winding encircling said flux paths; said control windings being wound in directions to provide, for said A.C. control signal, the same flux-directional relationship with respect to said output windings during the conducting half-cycles of said output windings respectively, so that the magnitudes of the currents flowing through said output windings will vary in the same direction with changes in amplitude of said A.C. control signal.

4. A magnetic amplifier comprising, in combination, a pair of coaxially-positioned balanced toroidal magnetic cores, a pair of output windings each wound around one of said cores, an A.C. energizing circuit arranged to feed current through said output windings respectively on alternate half-cycles of the A.C. supply voltage, a load element connected in series with said energizing circuit to receive said current, control winding means surrounding both of said flux paths, and circuit means establishing a short-circuited electrically-conductive path having first and second portions each at least substantially surrounding a respective one of said cores and together forming a short-circuited winding encircling both of said cores, said first and second portions being so interconnected that a current flowing in a given direction around said short-circuited winding will produce in said cores respective fluxes having the same directional relationship with respect to the corresponding fluxes produced by said output windings during the firing half-cycles thereof.

5. A magnetic amplifier as claimed in claim 4, wherein said control winding means consists of first and second separate windings each surrounding one of said cores, said first and second separate windings serving to define said first and second path portions respectively, said circuit means comprising a two-wire input circuit arranged to connect said first and second windings together to form said short-circuited winding.
